(57) **CLAIM**

The ornamental design for a clamp, as shown and described.

DESCRIPTION

FIG. 1 is a left, front perspective view from above of the clamp showing our new design;

FIG. 2 is a right rear perspective view from below of the clamp of FIG. 1;

FIG. 3 is a left side elevational view of the clamp of FIGS. 1 and 2;

FIG. 4 is a right side elevational view of the clamp of FIGS. 1-3;

FIG. 5 is a front elevational view of the clamp of FIGS. 1-4;

FIG. 6 is a rear elevational view of the clamp of FIGS. 1-5;

FIG. 7 is a top plan view of the clamp of FIGS. 1-6;

FIG. 8 is a bottom plan view of the clamp of FIGS. 1-7; and,

FIG. 9 is a left, front perspective view from above similar to FIG. 1, and showing the clamp in open condition.

The broken lines illustrated in the drawings depict environment and form no part of the claimed design.
